WASHING MACHINE MEANS FOR ELEVATING CLOTHES THEREIN

Anthony J. Georgilas, Detroit, Mich.

Application February 15, 1935, Serial No. 6,669

9 Claims. (Cl. 68—15)

This invention concerns improvement in washing machines generally, but has special reference to an improvement whereby when it is desired to remove a certain particle, or particles of clothing from the washing machine, the drum containing the clothes may be quickly and easily drawn to the top of the machine by the operator thereof, thereby exposing all particles of clothing so that any part thereof may be removed without the necessity of the operator of the machine reaching far into the same for this purpose, and as is customary in the old methods of machines of this type.

One of the objects of this invention is to provide an inexpensive and compact mechanical unit which is adapted to be coordinated with the clothes-agitating drum of the washing machine, and particularly in a manner so as to avoid interfering with the operating mechanism of the machine.

Other objects and advantages of the invention will become readily apparent during the course of the following detailed description, illustrated throughout the accompanying drawing, and more fully pointed out in the subjoined claims.

With reference to the drawing:

Figure 1 is a sectional view of the clothes-agitating drum of a washing machine, with the invention in connection therewith, and shown in a normally lowered position of said drum.

Figure 2 is a similar view to that of Figure 1, but showing the drum in a somewhat elevated position.

Figure 3 is a greatly enlarged view of the washing machine agitator shaft, with the invention associated therewith and broken as indicated.

Figure 4 is a plan sectional view taken directly upon line 4—4 of Figure 3.

Figure 5 is a view of the top portion of the washing machine agitator shaft, and showing how the device is dropped to the side when said shaft is in the position of its highest point relative to the machine.

Figure 6 is an upwardly deflected section taken upon line 6—6 of Figure 3.

Figure 7 is a horizontal view of the upper portion of the washing machine agitator shaft, showing one of the recesses provided upon each side thereof.

In presenting herewith my invention, it is to be understood that certain elements of the washing machine not a part of the invention will be designated by consecutive letters of the alphabet, while the invention proper will be characterized by the customary reference numerals.

The invention comprises principal U member 1, and having lug 2 upon each of the lower ends thereof, and said lugs being adapted to detachably engage respective apertures within sleeve member A of the washing machine. This is the means by which the device is attached to the machine.

It is understood that vertically disposed shaft B is associated with the agitator unit of the washing machine, which comprises vertically inclined radial blades C that are secured to base D, all of which are arranged as indicated within drum E, also cover F being for said drum.

An important feature of the invention is the simple manner in which shaft B is modified so that the invention may be coordinated with same, and this is accomplished by the act of machining elongated semi-circular recess 3 within each side of the shaft and extending from the position thereupon at lugs 2, continuously to the extreme top end of the shaft. The purpose of said recesses is to slidably receive U member 1 in the manner as prescribed.

U member 1 being permanently fixed with agitator sleeve member A, and the latter member being secured to base D, it is therefore clearly understood that the entire agitator unit may be elevated within drum E sufficiently so as to bring the clothes near or to the top of the drum so as to facilitate the removal of the clothes therein or part thereof, by the operator of the machine at his command.

When the agitator with the clothes therein is elevated, an improved method for locking the agitator in any predetermined elevated position is employed, and consists of swivel member 4, preferably designed as indicated in Figure 4, and in Figure 3 it is clearly observed that thumb actuator 5 is provided and is permanently fixed with swivel member 4, and also has depending shank 6 formed thereon, and said shank is adapted to engage an aperture provided within plate 7 in a manner so as to admit of the free swivelling motion of member 4 relative to plate 7. Said plate is detachably secured to the top end of shaft B by screws 8 where shown. Member 4 is first connected to plate 7 and cotter 9 inserted in shank 6, thence plate 7 is secured to said shaft by screws 8 as explained, in the assembling of said elements to shaft B. Counterbored recess 10 is provided within shaft B where shown so as to accommodate the free action of shank 6.

It being understood from previous explanation that member 4 is adapted to swivel upon shaft B, and in Figure 4 it is observed that said member is

provided with hooks 4A and 4B respectively and in opposed relation. Also U member 1 is provided with a plurality of uniformly spaced notches 11 so that at any desired elevation of the agitator upon shaft B, member 1 may be effectively locked in this position, and by the simple turning of member 4 sufficiently until hooks 4A and 4B thereon engage notches 11, as clearly indicated in Figure 4. It is further seen in this view that the normal position of member 4 is indicated by the dotted lines therein, and as being inoperative.

A very desirable feature of the invention is the method employed for deflecting member 1 to the position as shown in Figure 5. For this purpose said member will clear the wringer of the washing machine, and be otherwise out of the way when the agitator is elevated to the extreme top of drum E.

This is effected by providing a pair of elongated members 12, which have a round body similar to that of member 4, and are adapted to engage recesses 3 respectively, and being permanently retained in this position by lugs 2. Said lugs engage similar formed apertures within sleeve A as shown. The ends of member 1 pivotally engage the top end of members 12 by virtue of studs 13 where shown.

It is understood that when member 1 is dropped to the side as in Figure 5, the agitator may be locked in this elevated position, similar to the manner of locking member 1 in any predetermined position. This is made possible because of the fact that members 12 are each provided with a notch similar to notches 11, so that hooks 4A and 4B of member 4 may engage the first-named notches for this purpose.

While not a direct part of my invention, I would suggest as an improvement and so as to facilitate removing the clothes from drum E, that flexible rubber band G be provided, and of the formation and where indicated in Figure 1. The purpose of band G is to prevent particles of clothing from becoming lodged between the agitator and drum E during the operation of the washing machine, and thereby in this condition rendering such particles difficult to remove from the water in the machine.

Aperture 14 is provided where indicated in member 1 so as to receive the end of a hook or the like, but said hook is not shown in the drawing. The purpose of said hook is that in the event member 1 becomes too hot to contact by the hand, the hook may be readily applied without the necessity of injuring the fingers by burn, when said member is elevated for the purpose previously described.

While I have shown the preferred embodiment of the invention, it is to be understood that various changes in the size, shape and arrangement of parts may be resorted to without departing from the spirit of the invention and the scope of the appended claims.

Having thus fully described my invention, what I claim as new is:—

1. A washing machine including a drum, a rotatable shaft extending upwardly in the drum, an agitator slidably mounted on the shaft and rotatable therewith having a base substantially coextensive with the cross-sectional area of the drum, means carried by the agitator for raising and lowering the same, and means for holding the agitator in any one of a series of vertically adjusted positions on said shaft.

2. A washing machine including a drum, a rotatable shaft extending upwardly therein, an ag-

itator unit slidably mounted on said shaft and rotatable therewith having a base substantially coextensive with the cross-sectional area of the drum, a bail extending upwardly from the agitator unit for raising and lowering the agitator unit, and cooperating means between said member and the shaft for holding the agitator unit in any one of a series of vertically adjusted positions on said shaft.

3. A washing machine including a drum, a rotatable shaft extending upwardly therein, an agitator unit slidably mounted on the shaft and rotatable therewith having a base substantially coextensive with the cross-sectional area of the drum, a notched member extending upwardly from the agitator unit for raising and lowering the same, and a latch member swingably mounted on the shaft and cooperating with the notches in the notched member for holding the agitator unit in any one of a series of vertically adjusted positions on said shaft.

4. A washing machine including a drum, a rotatable shaft extending upwardly therein, an agitator unit slidably mounted on said shaft and rotatable therewith having a base substantially coextensive with the cross-sectional area of the drum, a bail extending upwardly from the agitator unit, and cooperating means between said unit and the shaft for holding the agitator unit in any one of a series of vertically adjusted positions on said shaft said bail being pivoted whereby it may be swung laterally and outwardly from the drum when the agitator unit is in its fully raised position so as not to interfere with removal of articles from the machine.

5. A washing machine including a drum, a rotatable shaft extending upwardly therein, an agitator unit slidably mounted on the shaft and rotatable therewith having a base substantially coextensive with the cross-sectional area of the drum, a sleeve included in said agitator unit, an inverted U-shaped bail extending over the top of the shaft and downwardly along the opposite sides of the shaft the ends of the arms of the inverted U-shaped bail being connected to the sleeve whereby the agitator unit may be raised and lowered, and cooperating means between the top of the shaft and the arms of the inverted U-shaped bail for holding the agitator unit in any one of a series of vertically adjusted positions on said shaft.

6. A washing machine including a drum, a rotatable shaft extending upwardly therein, an agitator unit slidably mounted on the shaft and rotatable therewith having a base substantially coextensive with the cross-sectional area of the drum, a sleeve included in said agitator unit, an inverted U-shaped bail extending over the top of the shaft and downwardly along the opposite sides of the shaft the ends of the arms of the inverted U-shaped bail being connected to the sleeve whereby the agitator unit may be raised and lowered, the arms of the inverted U-shaped bail being formed with vertically spaced notches, and a latch mounted on the upper end of the shaft for selective engagement with the respective notches for locking the inverted U-shaped bail and the agitator unit in any one of a series of vertically adjusted positions on said shaft.

7. A washing machine including a drum, a rotatable shaft extending upwardly therein, an agitator unit including a sleeve slidably mounted on the shaft and rotatable therewith having a base substantially coextensive with the cross-

- sectional area of the drum, a pair of members extending on opposite sides of the shaft, and connected at their lower ends to the sleeve, an inverted U-shaped bail straddling the top and 5 sides of the shaft the lower ends of the arms of said bail being pivotally connected to the upper ends of the respective members whereby the bail may be swung laterally and outwardly of the drum when the agitator unit is in a fully raised 10 position so as not to interfere with removal of articles from the machine, the bail forming a handle for raising and lowering the agitator unit and cooperative means between the shaft and the arms of the bail for holding the agitator 15 unit in any predetermined one of a series of vertically adjusted positions on said shaft.
8. A washing machine including a drum, a rotatable shaft extending upwardly therein, an agitator unit including a sleeve slidably mounted 20 on the shaft and rotatable therewith having a base substantially coextensive with the cross-sectional area of the drum, a pair of members extending on opposite sides of the shaft, and connected at their lower ends to the sleeve, an inverted U-shaped bail straddling the top and sides of the shaft and lower ends of the 25 arms of said bail being pivotally connected to the upper ends of the respective members whereby the bail may be swung laterally and outwardly of the drum when the agitator unit is in a fully raised position, the bail forming a handle for raising and lowering the agitator unit so as not to interfere with removal of articles from machine.

drum when the agitator unit is in a fully raised position so as not to interfere with the removal of articles from the machine, the bail forming a handle for raising and lowering the agitator unit, cooperative means between the shaft and the arms of the bail for holding the agitator unit in any vertically adjusted position, said members being provided with means for cooperation with the aforementioned means on the shaft for locking the agitator unit in its up- 10 permost position when the bail is in a laterally disposed position.

9. A washing machine including a drum, a rotatable shaft extending upwardly therein, an agitator unit including a sleeve slidably mounted 15 on the shaft and rotatable therewith, a pair of members extending on opposite sides of the shaft, and connected at their lower ends to the sleeve, an inverted U-shaped bail straddling the top and sides of the shaft and lower ends of the 20 arms of said bail being pivotally connected to the upper ends of the respective members whereby the bail may be swung laterally and outwardly of the drum when the agitator unit is in a fully raised position, the bail forming a handle 25 for raising and lowering the agitator unit so as not to interfere with removal of articles from machine.
